C. S. REED

GUN

Filed April 4, 1924

Charles S. Reed

W. H. Roach

Attorney

UNITED STATES PATENT OFFICE.

CHARLES S. REED, OF WATERTOWN, MASSACHUSETTS.

GUN.

Application filed April 4, 1924. Serial No. 704,225.

(GRANTED UNDER THE ACT OF MARCH 3, 1883; 22 STAT. L. 625.)

To all whom it may concern:

Be it known that I, CHARLES S. REED, a citizen of the United States, and a resident of Watertown, Mass., county of Middlesex, 5 and State of Massachusetts, have invented an Improvement in Guns, of which the following is a specification.

The invention described herein may be used by the Government, or any of its officers 10 or employees in prosecution of work for the Government, or by any other person in the United States, without payment to me of any royalty thereon, in accordance with the act of March 3, 1883.

15 The present invention relates to a method of and an apparatus for controlling the range of a gun.

The primary object of the present invention is the establishment of a method and 20 the provision of means whereby the energy generated by the propelling gases at the moment of explosion may be controlled in such a manner that with the same propelling charge different ranges may be attained.

25 With the foregoing and other objects in view, my invention resides in the steps constituting my process and in the novel arrangement and combination of parts and in the details of construction hereinafter described and claimed, it being understood that changes in the precise embodiment of the invention herein disclosed may be made within the scope of what is claimed without departing from the spirit of the invention.

30 For a long time efforts have been made to vary the range of a gun without varying the propellant or the angle of fire. Hitherto these efforts have met with little practical success. The present invention aims to overcome difficulties experienced in the use of other methods by providing the gun with a vent through which the gases from the explosion chamber may escape, and by controlling the area of this vent in such manner 35 that varying amounts of these gases will be allowed to escape from the gun with varying ranges.

A preferred embodiment of a control device adapted to be employed according to the method constituting this invention is 40 illustrated in the accompanying drawing, in which,—

Fig. 1 is a vertical section through a gun

barrel provided with a control device such as claimed;

55

Figs. 2, 3, 4, and 5 are detail sectional views illustrating the various positions of the control, and

Fig. 6 is a section on the line 6—6 of Fig. 2.

60

Referring to the drawing by numerals of reference:

I have shown a gun barrel 5 which is provided with a vent 6 at a point intermediate its length and in such position as 65 to permit escape of the propelling gases therethrough before the projectile has left the gun. The location of this vent will preferably be determined by experience and will depend upon the caliber of the gun, the 70 ranges at which the gun is to be fired, the type of projectile, etc.

In order to vary the range for a given projectile, a given propelling charge and a given angle of fire, I have found that if 75 some means is provided for controlling the area of the vent so as to permit more or less of the propelling gas to escape that the range of the gun may thus be directly controlled.

Any suitable means may be used for controlling the area of the vent. As shown I employ a valve 7 preferably rotatably mounted as upon a shaft 8 in the chamber

80

9 of a block 10, which is secured to the gun barrel and which is provided with an opening 11 adapted to register with the vent 6 of the barrel so that gases may pass directly from the gun into the chamber 9. The block

85

10 is further provided with a vent 12, communicating with the chamber 9, through which the propelling gases which escape from the gun may pass into the air. The valve 7 will preferably be of such structure as to permit a varying amount of gas to escape from the vent 6 with different settings 90 of the valve. In the preferred embodiment of my invention this valve will be provided with a number of openings 13 of various sizes which may be selectively brought into register with the opening 11. The valve 7 100

will preferably be so mounted within the recess of the chamber 9 as to prevent any leakage about the valve so that the gases may only escape from the gun through the particular valve opening 13 which has been 105 brought into register with the opening 11.

Preferably also, the valve will be provided with a recess or chamber 14 which in one position of the valve will act merely as a chamber within which the propelling gases may expand.

Figures 2, 3, 4 and 5 illustrate various positions of the valve. In Fig. 2, the smallest valve opening 13^a has been brought into register with the opening 11 and the vent 6. In this case the propelling gases pass through the vent 6, opening 11, and opening 13^a of the valve and will expand in the chamber 14 of the valve. In this case there will be no escape of the gas from the block 10, the chamber 14 of the valve acting merely as an expansion chamber for the gases from the explosion chamber 15 of the gun. In Fig. 3 a second open position of the valve is illustrated in which one of the valve openings 13^b has been brought into register with the opening 11 and another of the openings 13^a with the vent 12 of the chamber 10. In this position certain of the gases will escape through the vent 6, the opening 11, and the opening 13^b through the valve chamber 14 and the opening 13^a of the valve and the vent 12 to the air. A third position of the valve is illustrated in Fig. 4 where a greater proportion of the propelling gases may escape. The maximum opening of the valve is illustrated in Fig. 5.

To permit ready escape of the gases where the valve opening opposite the vent 6 is of considerable size the valve openings will preferably be so proportioned that the area of the openings opposite the vent 12 at any time will be equal to the area of the opening opposite the vent 6. In forming the chamber 9 within the block 10, therefore, it has been found preferable to make the recess within the block of greater size than the valve so as to permit free escape of the gases from the chamber 14 and vent 12 in any venting position of the valve.

Any suitable means may be employed for manipulating the valve. As shown, the valve is provided with a hand lever 16 and with a spring pressed catch 17, which is adapted to selectively enter in various adjusted positions of the valve suitable recesses 18 on a sector 19 secured to one side of the block 10.

The range of the projectile 20 may be controlled, then, by the various settings of the valve. In closed position the maximum effect of the propelling gases will be attained and the maximum range secured. In the first open position of the valve the capacity of the explosion chamber is merely increased. In the other open positions of the valve, varying amounts of the propelling gases are allowed to escape. By changing the setting of the valve, then, the range is controlled.

With a device of the type described, it is possible, then, to directly vary the range

with any angular setting of the gun without changing the propelling charge or without varying the projectile. The means by which the range is thus controlled is simple in operation, easy to construct, and will not readily get out of order. With this invention high angle fire guns may be readily employed for close range work as well as firing at comparatively long ranges.

Having thus described my invention, 75 what I claim is:

1. The combination with a gun provided with an explosion chamber of a second chamber secured to the gun and provided with a plurality of openings, one of said openings acting as a vent between the explosion chamber and the second chamber and another opening acting as a vent for the second chamber, a valve mounted in the second chamber and adapted to control the area of one of the vents, said valve provided with a chamber therein and with a plurality of openings of different area adapted to be brought selectively into register with one of the vents, said valve being so constructed 90 that in one open position thereof the propelling gases may escape from the explosion chamber to the chamber of the valve and in other open positions thereof the area of the opening opposite one of the vents will be 95 equal to the area of all openings opposite the other vent.

2. The combination with a gun provided with an explosion chamber of a second chamber secured to the gun and provided with a plurality of openings, one of said openings acting as a vent between the explosion chamber and the second chamber and another opening acting as a vent for the second chamber, a valve adapted to control the area of one of said vents, said valve provided with a plurality of openings of different areas adapted to be brought selectively into register with one of the vents, said valve being so constructed that when the valve is in venting position the area of the opening opposite one of the vents will be equal to the areas of all openings opposite the other vent.

3. The combination with a gun provided with an explosion chamber and with a vent for said explosion chamber, of adjustable means for controlling the area of said vent, said means being formed with a chamber adapted to communicate with the explosion chamber in one position of said adjustable means whereby the area of the explosion chamber is increased in said position, and means for locking the adjustable means in any adjusted position.

4. The combination with a gun provided with an explosion chamber and with a vent for said explosion chamber, of adjustable means for controlling the area of said vent, said means being formed with a chamber

adapted to communicate with the explosion chamber in one position of the said adjustable means, whereby the area of said explosion chamber is increased in said position.

5. The combination with a gun provided with an explosion chamber, of a second chamber secured to the gun and provided with a plurality of openings, one of said openings acting as a vent between the explosion chamber and the second chamber, and another opening acting as a vent for the second chamber, and means for controlling the area of both of the vents.

10. The combination with a gun provided with an explosion chamber, a second chamber secured to the gun and provided with a plurality of openings, one of the openings forming a vent between the explosion chamber and the second chamber, another of the openings acting as a vent from the second chamber to the atmosphere and means operable to selectively vary the area of such vents or to vary the capacity of the explosion chamber.

ber and the second chamber, another of the openings forming a vent for the second 20 chamber to the atmosphere, and means for controlling the area of such vents and providing an explosion chamber between the vents.

7. The combination with a gun provided 25 with an explosion chamber, a second chamber secured to the gun and provided with a plurality of openings, one of the openings forming a vent between the explosion chamber and the second chamber, another of the 30 openings acting as a vent from the second chamber to the atmosphere and means operable to selectively vary the area of such vents or to vary the capacity of the explosion chamber.

CHARLES S. REED.
